MACHINE FOR MAKING CIGAR BUNCHES

Sigurd Clausen, Brooklyn, N. Y., assignor to International Cigar Machinery Company, a corporation of New Jersey

Application June 2, 1937, Serial No. 146,008

22 Claims. (Cl. 131—42)

This invention relates to cigar machines, and more particularly to bunch rolling mechanisms for making composite bunches of long and short filler tobacco.

5 Of the two general types of cigars now made, the long filler cigar is usually more preferred by smokers due to the fact that it draws better, is relatively stronger insofar as breakage is concerned, has a firm "feel" and due to the long 10 filler used there is little likelihood that particles of the tobacco will work into the smoker's mouth during smoking of the cigar. With the short filler cigar particles of tobacco will invariably work into the smoker's mouth, thereby causing 15 some annoyance. Also, there is a difference in the smoking qualities of this type of cigar due to the fact that the filler which consists of small pieces of tobacco must be either concentrated or molded to shape and the air passages tend to be 20 restricted.

The present invention contemplates the formation of cigars generally of the short filler type but having added thereto some of the characteristics of a long filler cigar.

25 It is an object of this invention to provide a method of and apparatus for producing cigars which will have certain of the qualities of both long and short filler cigars.

It is also an object to provide a method of and 30 apparatus for forming composite cigar bunches of long and short filler by assembling the filler tobaccos in a novel manner so as to cause the long filler to hold the short filler in firm contact in a bunch and prevent the short filler from working out at the ends of the bunch.

35 It is a further object to provide a method of and machine for forming composite cigar bunches which includes forming a layer of long filler tobacco of predetermined size and thickness, placing a charge of short filler thereon and forming a bunch therefrom.

It is a further object to provide mechanism for 40 forming composite cigar bunches in which means for conveying layers of long filler tobacco cooperates with short filler feeding mechanism to associate both types of tobacco for formation into a composite bunch.

The invention also consists in the provision of 45 novel means for forming and conveying charges of long filler tobacco.

The invention also consists in mechanism for 50 forming improved cigars generally of the short filler type in which long filler tobacco is rolled in and around the short filler to form a composite bunch which results in a cigar having more body,

more stiffness and strength, and better smoking qualities.

With these and other objects not specifically mentioned in view, the invention consists of certain combinations and constructions which will 5 be hereinafter fully described, and then set forth more specifically in the appended claims.

In the accompanying drawings which form a part of this specification and in which like characters of reference indicate the same or like 10 parts:

Fig. 1 is a fragmentary perspective view of a cigar machine constructed in accordance with my invention;

Fig. 2 is a fragmentary perspective front view 15 of certain positions of Fig. 1;

Fig. 3 is a side elevation of the long filler mechanism;

Fig. 4 is a front elevation of certain parts shown in Fig. 3;

Fig. 5 is a sectional side elevation of the transfer device, taken on line 5—5 of Fig. 6;

Fig. 6 is a plan view of the same, taken on line 6—6 of Fig. 5;

Fig. 7 is also a sectional side elevation of the transfer device, showing the delivery of the long 25 filler charge upon the rolling apron;

Fig. 8 is a plan view of the foot pedal control device;

Fig. 9 is a side elevation of the foot pedal control mechanism; and

Fig. 10 is a partial sectional view showing a charge of long filler tobacco positioned in the loop in the rolling apron, with the short filler measuring device depositing a charge of short 30 filler tobacco in the loop of the belt.

Referring to the drawings, the frame 11 of the cigar machine supports a table 12 upon which a bunch rolling table 13 is mounted. A bracket 14 fixed to the frame 11 provides a support for a long filler transfer device, indicated generally at 40 18, which effects the transfer of charges of long filler tobacco to the rolling mechanism.

The transfer device 18 is mounted for lateral or tilting movement to and from bunch rolling table 13, and also for movement above the table to and from the short filler feeding mechanism indicated generally at S. The device 18 is mounted for movement to and from feed S on a lever 21 pivoted at 16 on bracket 15 which forms a part 45 of bracket 14. Attached to lever 21 at 20 is an adjustable link 19 which is also pivotally connected at 23 to lever 22 fulcrumed on shaft 17, which lever is provided with a cam follower 26 engaging with a cam 24 on shaft 25 to impart the described 50 55

swinging movement to the long filler transfer device 18. A rod 27 adjustably secured to transfer device 18 at 56a and to an extension on lever 21 at 27a cooperates with members described herein-after to produce a parallel motion in the movement of the transfer device to and from charge receiving and charge emptying positions. The transfer device in the form illustrated comprises a chamber or pocket 28, shown in Figs. 1 and 2. 5 This chamber is furnished with a door 29 which is normally kept in closed position, but which for illustrative purposes is shown open. See Figs. 2, 3, 5 and 6.

The door 29 is pivotally mounted at 35 in supports 36 suitably secured to the upper plate 37 of the transfer device 18. A lower plate 38 is connected to upper plate 37 by members 39, 40 and 41, and the two plates 37 and 38 are spaced from each other a suitable distance in order to provide 10 a chamber 28 of sufficient size and depth to accommodate charges of long filler tobacco, placed therein by the machine operator. The layer of tobacco which is usually rather thin may be constituted of one or more leaves spread out on 15 the bottom plate 38 of the chamber, and laid one over the other to form a charge of tobacco of the desired thickness. A lip 29a is carried by the door 29 to enable it to be opened or closed manually, although means are also provided for automatically opening and closing it.

A lever 30 mounted on the fulcrum shaft 17 oscillates the transfer device 18 laterally across the rolling table 13 (Fig. 3) by means of an adjustable link 32 connected at 33 to lever 30 and 20 at 32a to lever 31. Cam 24 actuates the lever 30 through a cam follower 34 mounted thereon to position the transfer device 18 over the rolling table 13 prior to its being operated forward for coaction with the short filler feed mechanism S. 25 The feed mechanism may be of the general type disclosed in Patent 2,021,652 to J. F. Halstead, granted November 19, 1935, in which short filler tobacco is fed from a magazine M, and will not be described further.

When a charge or layer of long filler tobacco has been conveyed by transfer device 18 to discharge position it is ejected from the chamber 28 by means of an ejector or plunger 42 slidably mounted between members 37 and 38. The 30 ejector 42 is operated by means of a lever 43 fulcrumed at 44 on lever 31, connected to a link 51 at 50, the other end of which link is joined at 52a to a lug 52 pivoted to a guide rod 42a held by a forked block 44a attached to ejector 42. The plunger 42a, which acts as a guide for the ejector, is mounted in forked block 44a and is guided in a bushing 42b held by the transfer supporting lug 55a mounted on the lower side of the bottom transfer device plate 38. A universal joint 46 attached to one leg 43b of the lever 43 permits a rod 47 to communicate motion from a lever 48 pivoted at 49 to the lever 43 which operates the ejector 42 to push the thin layer of long filler 45 sideways from the transfer 18 onto table 13 without disturbing the uniformity of the layer or affecting the arrangement of the leaves forming the layer.

In order to allow the door 29 to be opened or closed at the wish of the operator a block 36a located adjacent one end thereof, is provided with openings for the reception of a spring detent 53 carried by lever 55 loosely mounted on the door support between blocks 36 and 36a, as shown in Figs. 4 and 6. It is evident, therefore, that by 50 merely raising or pushing down on lip 29a the

connection between the detent on lever 55 and openings on block 36a can be broken and the door moved manually to the required position. This arrangement has been provided in order to allow the operator to inspect the charge, have access to the chamber at all times, and also to place additional charges in the chamber if it should be desired before the end of the cycle of machine operations.

The door is automatically opened and closed by means of the mechanism that operates the ejector. Referring to Figs. 3, 5 and 6, it will be seen that lever 55 has connected thereto a link 54, which has formed at its other end an elongated slot 56a in which is adapted to move a pin 56b mounted on block 44a. Therefore, on the extreme forward movement of block 44a pin 56b will engage the forward end of slot 56a which will cause lever 55 to rock, and through the detent engagement described cause the door, if 10 open, to close. On the extreme rearward movement of the ejector a similar engagement of pin 56b with the rear end of slot 56a causes the door to open.

In the operation of this device an operator at 25 A builds up a suitable number of long filler tobacco leaves in the chamber 28, thereby forming a layer of predetermined size and thickness, the lever P is depressed and the tilting mechanism operates to first swing the transfer device laterally 30 across the bunch rolling table 13 and then towards the short filler feeding mechanism S. By means of the lever 31 and rods 27, the transfer device always moves in a plane parallel to the rolling table so that it is properly positioned 35 above the same for correct ejection of the long filler as a substantially intact layer onto the belt of the rolling mechanism. The block 44a is then moved forward by movement of lever 43 and ejector 42 moves the layer of long filler tobacco 40 onto the belt F of the rolling mechanism and positions it beneath the short filler feeding member S which thereupon moves down, forms a loop in the belt (as shown in Fig. 10), and deposits its charge upon the long filler tobacco placed to receive it. The operator at B places a binder on 45 the rolling table and presses foot pedal P' after which operation the machine is in readiness to carry out its prescribed function of rolling the assembled long and short filler together with the 50 binder into a composite bunch. In order to control the operation of the bunch making machine, the latter is equipped with two foot pedals P and P', of which pedal P is used by the operator attending to the transfer device 18, while pedal P' 55 is actuated by the bunch machine operator, both pedals being connected with a clutch control mechanism and connecting members of conventional design, as shown in Figs. 8 and 9, in such a way that the machine cannot be started unless 60 both foot pedals are depressed by the attendants. The machine makes one complete cycle and then automatically stops.

Foot pedal P is mounted on a shaft 60 supported by bearings of the frame 11. To said 65 shaft is also fastened a lever 61 (Figs. 8 and 9) carrying a stud 62 engaging with a slot 63 of a toggle bar 64 which is pivoted to a lever 65 which is loosely mounted on shaft 60. Lever 65 by means of a slotted lug 66 and an adjusting 70 bar 67 carries the foot pedal P'. To the center portion of toggle bar 64 is fastened a stud 68 engaging with a slot 69 of the lower portion of a vertical control link 70, the upper end of which is pivoted to the center portion of a toggle joint 75

11. One end of the toggle joint is pivoted to a clutch operating lever 12, while the other end is pivoted to a toggle control lever 13. The latter is loosely mounted on a stud 14 (Fig. 9) held by the main frame 11. The clutch operating lever 12 is pivoted to a stud 15 and is equipped with a throw-out lever 16 carrying a follower 17 engaging with a collar 18 actuating a clutch cone 19 of a clutch 10 mounted on the main drive shaft 11 of the machine. Clutch cone 19 is slidably mounted on shaft 15 and collar 18 is equipped with a tension spring 13 held by a collar 14 also fastened to shaft 15. The latter carries a worm 15 engaging with a worm gear 16 driving the main cam shaft 25 of the machine. To shaft 25 is attached a cam lug 17 provided for the purpose of disengaging the clutch automatically after each cycle of the machine. Levers 61 and 65 of vertical link 70 are equipped with tension springs 20 88, 89 and 90, respectively, all of which are anchored to a stud 91 (Fig. 9) held by a plate 92 fastened to frame 11. Plate 92 also carries a pair of lugs 93, each of which supports an adjustable stop screw 94 provided for the purpose 25 of checking the lowermost positions of levers 61 and 65.

The several means referred to may be varied in construction within the scope of the claims, for the particular device selected to illustrate the invention is but one of many possible concrete embodiments of the same. The invention is not therefore to be restricted to the precise details of the structure shown and described.

What is claimed is:

35 1. A cigar machine for rolling short filler in long filler to form composite bunches, comprising a transfer mechanism for said long filler, said transfer having means for positioning said filler for transfer therein and discharge therefrom, a bunch rolling device, means for moving said mechanism over said device, and means for ejecting said filler tobacco onto said device.

40 2. A cigar machine comprising a bunch rolling mechanism, a member arranged to receive predetermined quantities of long filler tobacco in layers, means to eject said layers as a unit from said member to said mechanism, means for delivering a charge of short filler tobacco upon each layer of long filler tobacco after it has been placed upon said mechanism, and means for rolling said associated tobaccos into a composite bunch.

45 3. In a cigar machine, the combination with a bunch rolling mechanism, of a conveyor for transferring a layer of long filler tobacco to said mechanism, said conveyor including a pocket into which said filler is placed, and an ejector for forcing said tobacco from said pocket.

50 4. In a cigar machine, the combination with a bunch rolling mechanism, of a conveyor for transferring a layer of long filler tobacco to said mechanism, said conveyor including a chamber into which said filler is placed, an ejector for forcing said tobacco from said chamber, means for delivering a charge of short filler upon said long filler, and means for operating said mechanism to roll said short and long filler into a composite bunch.

55 5. The method of forming composite long and short filler cigars which consists of forming a layer of long filler tobacco of predetermined size and thickness, transferring said layer to a rolling station forming a measured charge of short filler tobacco, placing said charge on said long filler layer at said station, and then rolling said 60 layer and charge together to form a composite

bunch in which the long filler encloses said short filler and holds it relatively fixed in said bunch.

6. The method of forming cigars which comprises placing a charge of short filler tobacco on a layer of long filler tobacco of predetermined size and thickness, forming a loop in said long filler to receive said charge of short filler, rolling said long and short filler together to form a composite assembly, enclosing said assembly in a binder to form a bunch and then wrapping said bunch.

7. The method of forming cigars which comprises placing a layer of long filler tobacco of predetermined size and thickness on a rolling table and forming a loop in said layer, depositing a charge of short filler tobacco on said layer in said loop, rolling said long and short fillers together to form an incomplete bunch assembly, and then rolling said assembly in a binder to complete the formation of a composite bunch.

8. In a cigar machine, mechanism for transferring layers of long filler tobacco to a rolling table, comprising a rockable support, a pair of spaced plates mounted on said support and forming a tobacco positioning pocket, means for moving said mechanism to and from said table for discharging and loading said pocket, and an ejector for discharging said layers of tobacco from said chamber.

9. In a cigar machine, the combination with a bunch rolling mechanism, of a tobacco conveying device comprising a transfer member, a pivoted support for said member, means for moving said member transversely to said mechanism to bring it over said mechanism, and means for moving said member longitudinally to bring it to discharging position, and an ejector mounted on said member for ejecting said layer from said member onto said mechanism.

10. In a cigar machine, a filler transfer mechanism, comprising spaced plates, one of said plates having an opening therein, and a pivoted door secured adjacent said opening, said opening forming a chamber with the other plate for the reception of a layer of filler tobacco, an ejector for ejecting said tobacco from said opening carried by said mechanism, and means for moving said mechanism to and from discharging position.

11. In a cigar machine, a filler transfer mechanism, comprising a horizontal bottom plate, a top plate spaced above said bottom plate, said top plate having an opening therein defining with the bottom plate a tobacco layer receiving and measuring chamber, a bunch rolling table, means mounting said transfer mechanism for movement to and from said table, and means for discharging layers of filler tobacco from said mechanism onto said table.

12. In a cigar machine, the combination with a bunch rolling mechanism, of a filler transfer device, said device including a plurality of spaced plates, one of which is provided with an aperture defining with the other plate a tobacco layer forming and transferring pocket, a door mounted adjacent to and adapted to close said aperture, automatic means for opening and closing said aperture, and additional means mounting said door for manual operation.

13. In a cigar machine, the combination with a bunch rolling mechanism, of a filler transfer device, said device including a plurality of spaced plates, one of which is provided with an aperture defining with the other plate a tobacco layer forming and transferring chamber, a door mounted adjacent to and adapted to close said aperture,

- automatic means for opening and closing said door, additional means for opening said door manually, said door operating means comprising a loosely mounted lever, a detent carried by said lever, a block fixed to said door and provided with recesses for effecting a connection between said detent and door for automatic movement, the engagement between the lever and block being so arranged that manually applied force 5 will break said connection and release said door for manual opening or closing.
14. In a cigar machine, a bunch rolling table, a filler transfer mechanism, means mounting said mechanism for movement to and from said table, 10 said means comprising a lever supporting said mechanism for movement in one plane and a second lever supporting said first named lever for movement in a plane at right angles to said first plane of movement.
15. In a cigar machine, a bunch rolling table, a filler transfer mechanism including a transfer chamber, means mounting said chamber for parallel motion over said table, said means including a lever supporting said table for lateral 15 movement to and from said table, a second lever supporting said first lever, and means for rocking said second lever to swing said chamber longitudinally over said table.
16. In a cigar machine, a bunch rolling table, 20 a filler transfer including a chamber for transferring layers of long filler leaves, an ejector mounted in said chamber for discharging said layers therefrom, a rockable support for said mechanism arranged to swing said mechanism in one plane over said table, a lever mounting said 25 support and arranged to swing said mechanism in a plane at right angles to the first mentioned plane, and means on said support for moving said ejector to and from ejecting position.
17. In a cigar machine, a bunch rolling apron, means for feeding separate portions of long filler tobacco in a laminated assembly to said apron, means for feeding separate portions of short filler tobacco to said apron upon said assembly, and 30 means for rolling said assembly portions into composite cigar bunches.
18. The method of forming composite cigar

bunches which comprises forming a separate charge of short filler tobacco, forming a thin layer of long filler tobacco of predetermined dimensions, associating said two filler tobaccos to form a partial bunch with the short filler located 5 in a pocket formed in the long filler tobacco, and rolling said partial bunch in a binder to complete the formation of said composite bunch.

19. The method of making cigars which consists of forming a charge of short filler tobacco, 10 arranging long filler tobacco leaves in a restricted area to form a thin layer of predetermined size and thickness, moving said layer edgewise into position for association with said short filler and rolling said long and short filler tobaccos into a 15 composite bunch.

20. In a cigar machine, the combination with a bunch rolling mechanism, of a conveyor for transferring a layer of long filler tobacco, said conveyor comprising a shallow pocket into which 20 one or more tobacco leaves are placed to form a thin layer of long filler tobacco, and means for pushing said layer edgewise from said pocket into said mechanism, said means being so arranged that in its movement it removes said layer from 25 said pocket in substantially the arrangement it assumed while in said pocket.

21. In a cigar machine, a device for forming a charge of short filler tobacco, means for conveying a charge of long filler tobacco for assembly 30 with said short filler into a composite bunch, said means including a pocket in which leaves are arranged in a thin layer, and means for moving said layer edgewise from said pocket in complete 35 layer formation for association with said short filler.

22. In a cigar machine, the combination with bunch rolling mechanism, of means for feeding assembled units of long filler tobacco, means for forming and feeding separate charges of short 40 filler tobacco, means for moving said long filler unit onto said mechanism and into position for assembly with said short filler tobacco, and means for positioning said short filler charges on said long filler units for assembly therewith into a 45 composite cigar bunch.

SIGURD CLAUSEN.
